HAIR WINDING DEVICE

Charles Frederick Hardy, Mitcham, England

Application February 25, 1948, Serial No. 10,680
In Great Britain January 15, 1947

1 Claim. (Cl. 132—33)

1

This invention relates to hair dressing appliances and more particularly to a device for use when giving a permanent wave.

When giving a permanent wave, it is the usual practice to curl the hair by hand which involves winding it on to a curling pin or holder, the hair, in this tight curled position, subsequently being subjected to treatment to produce the permanent wave.

This operation of winding the hair on to the holder is a tedious one since it takes considerable time, being done entirely by hand. Moreover even when the hair has been wound on to the holder, it is necessary to wind over the hair, strip material as a protecting medium and/or containing certain solutions or preparations for treating it, to "fix" the wave.

This invention has for its object to provide a hand appliance by means of which the hair can be automatically wound on to the holder.

According to the present invention, a hair dressing and winding appliance comprises a hand frame adapted to be rotated by hand or in a machine, and means adapted detachably to receive and support in the frame a curling pin or holder during the winding on or curling operation, which frame is provided with hair receiving elements, by means of which a length of hair to be wound on to the holder can be secured in position and guided or otherwise fed in an axial direction along the holder during winding rotation of the winding device.

In operation, a single tress or two tresses of hair are fastened to the holder by insertion in the hair receiving elements of the winding device, and after threading it through the appropriate guides, the winding device is caused to rotate so that it is wound on to the holder which remains stationary.

The invention is illustrated in the accompanying drawings in which Figure 1 is a diagrammatic view of curling rod or holder with a tress of hair engaged therewith. Figure 2 is a sectional elevation of the winding device of this invention with the rod or holder in position and prior to winding the hair on to the rod. Figure 3 is a transverse section drawn to a larger scale, on the line 3—3 of Figure 2, but showing the holder in the open position. Figure 4 is a bottom plan view of a hair receiving element carried by a sleeve which is shown in section.

2

In the drawings T indicates generally a tress of hair shown attached to a dummy head H but in practice the operator would pick up a tress of the person's hair in a similar manner.

5 Referring now to Figure 1 the curling rod or holder on to which the hair is wound preparatory to being subjected to a permanent waving treatment comprises a spindle 1 having a flanged arcuate head 2. On the head 2 is pivotally secured a lip piece 3 having a tongue 4 adapted to cooperate with a similar tongue 5 on the fixing portion of the flange 2. In use the root end of a tress of hair is first engaged between the tongue 4, 5 of the interlocking tongues where it is automatically gripped.

The spindle 1 of the holder is now inserted into the hollow interior of a sleeve 10 forming part of the winding member shown in Figure 2. This member essentially comprises a lateral arm or arms, indicated generally at 11, into which the tress of hair T is passed being releasably held therein so that by causing the sleeve 10 to rotate about the spindle 1, the hair will be wound on to the spindle of the curler at the same time 15 as it is withdrawn from the hair receiving element or elements 11.

In Figure 2, for clearness only, one tress is shown being wound on to the spindle but if desired two separate tresses can be passed between the lips 4, 5 on the under side of which they part and are entered one in each of the arms 11.

Each arm or hair receiving element, which, as shown, is preferably set at an acute angle to the 35 axis of rotation may be in the form of a tube through which the tress of hair is threaded.

For convenience in inserting the hair in the interior of the tube, the latter comprises inner and outer sleeves 12, 13, each provided with a longitudinal slot 14, 15 normally out of registration with one another so that the hair is totally enclosed in the interior of the tube. The two sleeves 12 and 13 may be held in their closed position by spring means including a coil spring 40 16 one end of which is anchored to a lug 17 on the outer sleeve 13, the other end being attached to a stud 18 fast with the inner sleeve 12 and extending through an L-shaped slot 19 in the outer sleeve. In the position shown in 45 Figure 2 the slots 14, 15 are closed but by moving the stud 18 along the slot and into the circum-

ferentially extending portion 19' thereof, the inner sleeve 12 can be rotated to bring the slot of the inner sleeve opposite the opening in the outer sleeve as shown in Figure 3.

21 is a hand grip to enable the device to be rotated by hand. A bracket 24 mounting a bobbin 25 of coloured tape or string may be provided so that the hair as it is wound on to the curler can be bound in position.

What I claim is:

In a hair dressing appliance, a hair former, a winding member including a tubular portion to receive the former and which is free to slide and rotate thereon as hair is wound onto said former, and hair receiving and guiding means fast on the winding member for guiding the hair into position on the former as the winding member revolves and slides, said guiding means including two independent hair receiving elements for winding separate tresses of hair on to the former, 20 which elements are disposed on opposite sides of the winding member and set at an angle less than a right angle to the winding axis, each

element being of tubular construction and comprising inner and outer tubular members each provided with a longitudinal opening, a stud attached to said inner tubular member, an L-shaped slot in said outer tubular member with which said stud co-operates, and a spring anchored at one end to the stud and at its other end to the outer tubular member for normally maintaining the openings in the tubular members out of registry with one another.

CHARLES FREDERICK HARDY.
